(57) **CLAIM**

The ornamental design for a vehicle bonnet vent, as shown and described.

DESCRIPTION

FIG. 1 is a front left perspective view of a vehicle bonnet vent according to the present invention.

FIG. 2 is a front right perspective view of the vehicle bonnet vent shown in FIG. 1.

FIG. 3 is a rear left perspective view thereof.

FIG. 4 is a rear right perspective view thereof.

FIG. 5 is a front view thereof.

FIG. 6 is a rear view thereof.

FIG. 7 is a left side view thereof.

FIG. 8 is a right side view thereof.

FIG. 9 is a top view thereof.

FIG. 10 is a bottom view thereof; and,

FIG. 11 is a top right side view of the vehicle bonnet vent shown in FIGS. 1-10, but mounted on a vehicle bonnet, with the rest of the vehicle shown in de-emphasized and half-tone portions so as to illustrate environmental structure.

More particularly, in FIG. 11, the inventive vehicle bonnet vent is shown within the broken line, and the elements shown outside the broken line form no part of the claimed invention, but are instead included to show environmental aspects thereof.
